G. E. ROHMER,

VAULT LIGHT.

APPLICATION FILED JAN. 24, 1918.

1,363,016.

Patented Dec. 21, 1920.

UNITED STATES PATENT OFFICE.

GABRIEL E. ROHMER, OF BROOKLYN, NEW YORK.

VAULT-LIGHT.

1,363,016.

Specification of Letters Patent. Patented Dec. 21, 1920.

Application filed January 24, 1918. Serial No. 213,512.

To all whom it may concern:

Be it known that I, GABRIEL E. ROHMER, a citizen of the United States, and resident of the borough of Brooklyn, in the county of 5 Kings and State of New York, have invented certain new and useful Improvements in Vault-Lights, of which the following is a specification.

The present invention relates to improvements in vault lights, and the embodiment of the invention disclosed herein, by way of example, is described with particular reference to such lights for plunge baths, although it will be understood that the invention may be utilized for other purposes, such for instance as side wall lights, theater foot lights, step lights and the like.

Much difficulty has been experienced in the past in providing plunge baths with lights. 20 These lights which have heretofore been provided were very impractical because of the great expense of installing the same, and the inability to provide proper reflectors which would at the same time permit of 25 convenient access to the electric lamps for renewal or other attention. These attempts in the past to provide lights for plunge baths have in most cases followed an arch or trench construction under the bottom and 30 sides of the plunge bath, which necessitated a considerable change in the usual construction of the bath, requiring special reinforced concrete construction, and materially weakening the whole structure.

35 It is an object of the present invention therefore to provide means by which such plunge baths may be illuminated at the bottom and sides in a manner which will simplify the construction of the bath, and without danger to its solidity, and which will afford accessibility for installation and renewal of lamps. A further object of the invention is to provide such means in the form of individual reflecting units, preferably 40 formed of terra cotta, and provided with an enameled surface which will serve to reflect the rays of light into the plunge bath.

Another object of the invention is to protect the electrical connections and the lamps 45 themselves from moisture from the bath, and to provide an improved vault glass construction which will permit passage of the rays of light into the plunge bath, and will form a continuous surface with the bottom or sides of the bath as the case may be. A 50 still further object is to provide ventilating

means for carrying off the carbon dioxid or other noxious gases which may form and accumulate in the passage through the illuminating units, which are usually at the lower- 55 most part of the buildings.

With these and other objects in view, embodiments of my invention are shown in the accompanying drawings, and these embodiments will be hereinafter more fully described with reference thereto, and the invention will be finally pointed out in the claims.

In the accompanying drawings:

Figure 1 is a longitudinal sectional view 70 of a plunge bath provided with an embodiment of my improved vault lights;

Fig. 2 is a transverse vertical section thereon;

Fig. 3 is a cross sectional view of one of 75 the illuminating units;

Fig. 4 is a vertical sectional view thereof;

Fig. 5 is a plan view of the same;

Fig. 6 is a vertical sectional view of the 80 type of unit provided at one end of the passage provided beneath the plunge bath;

Fig. 7 is a vertical sectional view of the 85 type of unit provided at the entrance end of the passage beneath the plunge bath;

Fig. 8 is a vertical sectional view of a 90 modified form of illuminating unit; and

Fig. 9 is an enlarged fragmentary view showing a modified means of hanging the lights.

Similar reference characters indicate corresponding parts throughout the several figures of the drawings.

Referring to the drawings, and more particularly to Figs. 1 and 2 thereof, in which there is shown a typical form of plunge bath 95 10, the bottom of the plunge bath is provided longitudinally with a channel 11 in which are placed the illuminating units 12.

These units are placed end to end as shown in elevation and section in Fig. 1, and 100 are formed preferably of enameled terra cotta for reflective purposes, and to prevent absorption of moisture. With the exception of the end units which will be hereinafter referred to, the units are provided with a circular bore 13 extending entirely through the same, and having an open portion 14 at the upper side of the unit. The bore of the unit and the upper surface 15, and also other parts if desired, are coated with an enamel 110 facing 16, the enamel concave surface of the bore 13 rendering the same highly re-

fective. The open portion 14 of the unit is provided at each side with a ledge 17, spaced from the upper surface 15 of the unit, and upon these ledges there is supported a frame 18 of gridiron formation, in which are set vault glasses 19. The ledges 17 are provided with grooves 17^a into which fit ribs 18^a of the frame to make a water tight joint.

The joints 20 between the vault glasses are 10 made water tight by means of plastic tar cement. The frames for the vault glasses may be provided upon individual units if desired, and suitably joined when the units are assembled, or one frame may extend continuously along the length of the plunge bath.

A groove 12^a is provided at the bottom of 20 the units, these grooves forming a continuous channel when the units are placed end to end, for the purpose of collecting and throwing off moisture which might occur should any moisture be condensed in the units. Of course, while the illumination is going on, there would be heat enough to 25 avoid this, but during periods where the same is not used, moisture would accumulate and make it disagreeable to the man who has to go in for the purpose of installing lights. Where the units are used on a 30 slope, the groove may if desired be dispensed with.

At suitable intervals on the under side of 35 the frame 18 there are provided depending bracket portions 21, having openings 22 therein, which are adapted to support the electric wire pipe 23, upon which there are provided the electric incandescent bulbs 24. These bulbs may be spaced as desired, and 40 are preferably disposed at an angle of 45° to the perpendicular axis of the unit. This enables the rays of light to be reflected by the concave enamel surface of the bore 13 in the most effective manner. Pockets 12^b and 12^c are provided on the interior of the 45 units, which enables the lights to be supported by branches 23^a of the pipe 23, as shown in Fig. 9. This enables the lights to be installed before the frame 18 is put in place.

The passage or canalization formed beneath the plunge bath by the units, is of an appropriate size, so as to permit a man to draw himself through the same upon his back, and have proper movement of his arms, so as to renew the lamps or otherwise 55 attend to the electric light equipment. Any suitable number of passages may be provided beneath the plunge bath, according to the amount of light desired, and the same form of units may be provided at the sides to illuminate the side walls.

At the end of the passage, I provide a special form of ventilating unit, closed at one end as at 25, and provided with an opening 26 therein in which there is secured an 60 outlet pipe 27. This ventilation of the re-

flector passages is necessary as such plunge baths are usually in the lowermost portion of a building, and permit of the accumulation of carbon dioxid or similar noxious gases, which would endanger the life of the 70 operator working in the passage.

At the entrance end of the passage I provide a unit such as shown in Fig. 7, which is placed adjacent the man hole 28^a, and is provided at its upper side with a bridge portion 75 28 adapted to form a support for the tiled sides of the plunge bath. A recessed corner portion 29 is provided in line and flush with the concave base corner tiles which extend entirely around the bottom perimeter of the 80 plunge. The ventilating unit is similarly bridged as at 30, and is provided with a concave corner portion 31.

In Fig. 8, I have illustrated a modified 85 form of reflector unit 32, having a concave portion 33 coated with enamel to form a reflecting surface, the lamps being disposed in a channel 34. The vault glasses 35 are secured by plastic tar cement 36 in the vertical side 37 of the unit. This type of reflector unit is particularly adapted for vertical indirect lighting, the concave surface 33 reflecting the light in a lateral direction, while the light itself is hidden in the channel 34. 90

My improved reflector unit, it will be seen, has a highly reflective inner surface which effectually distributes and reflects the light through the vault glasses. The units are assembled in such manner as to provide a passage or channel beneath the plunge bath, which will permit of the lamps being conveniently reached. The electrical connections are entirely protected from moisture, and as the reflector units may form a substantial part of the construction of the bath, and their upper surfaces have a smooth tile-like surface, they will not add materially to the cost of the bath, taking the place where they are substituted for the tile bottom of 105 the bath of the tile itself.

My invention will adapt itself to many uses where a lighting unit is desired, such for instance as in the vertical or horizontal lighting of side walls, foot lights for the 110 stage, step lights, side walks and the like. The same may be formed of terra cotta, as also pointed out, cast iron or other suitable structural material.

I have illustrated preferred and satisfactory embodiments of my invention, but it is obvious that changes may be made therein within the spirit and scope thereof, as defined in the appended claims.

I claim:

1. A lighting unit of the character described, comprising an open end container member substantially U-shaped in cross section open at its upper side and provided with an inner reflective surface, said con- 130

- tainer being impervious to light at both its upright and its bottom portions and adapted to be laid end to end with corresponding units to form a continuous channel, means 5 pervious to light entirely covering the open upper side of said container member opposed to said reflective surface, a watertight connection between said last named means and said container member, and 10 illuminating means disposed in said bore above said reflective surface and adapted to reflect the rays of light therefrom through said means pervious to light.
2. A lighting unit of the character described, comprising an open end container member substantially U-shaped in cross section open at its upper side and provided with an inner reflective surface, said container being impervious to light at both its 15 upright and its bottom portions and adapted to be laid end to end with corresponding units to form a continuous channel, means pervious to light entirely covering the open upper side of said container member opposed to said reflective surface, a watertight connection between said last named means and said container member, and illuminating means disposed beneath said means pervious to light, and spaced from the bottom 20 of said container to provide a space within the container to permit the passage of a man's body therethrough.
3. A lighting building unit, comprising an open end container member, having a bore, 25 and provided with a glazed inner reflective surface, a vault glass frame supported at the side of said container opposed to said reflective surface, vault glasses cemented in said frame to form a water tight covering 30 for said container member, a depending bracket carried by said frame, and illuminating means supported in said bore by said bracket, said reflective surface adapted to reflect the rays of light therefrom through 35 said vault glasses.
4. A lighting building unit, comprising an open end container member having a bore, and provided with a glazed inner reflective surface, a vault glass frame supported at 40 the side of said container opposed to said reflective surface, vault glasses cemented in said frame to form a water-tight covering for said container member, supporting means disposed in said container relatively 45 close to said vault glass frame and extending transversely across said container, and illuminating means supported thereby, the lower portion of said container between said 50 illuminating means and said reflecting surface forming an unobstructed channel.
5. The combination with a structure to be illuminated, of a plurality of illuminating units built into said structure, and comprising open end container members open at the 55 upper side, each provided with a bore com-
- municating with the bore of the adjacent unit, said bore having a glazed reflective surface, continuous means pervious to light covering the open side of said containers opposed to said reflective surface, and illuminating means disposed in the upper portion of said bore, said reflective surface adapted to reflect the rays of light therefrom through said covering means, the canalization formed by said successive bores adapted to permit 60 the passage of a man's body therethrough beneath said illuminating means.
6. The combination with a structure to be illuminated, of a plurality of illuminating units built into said structure, and comprising one piece open end container members open at their upper sides, each provided with a bore communicating with the bore of the adjacent unit, said bore having a glazed reflective surface the upper side of said 65 units being flush with said structure to be illuminated and constituting a continuous surface therewith, continuous means pervious to light covering the open side of said containers opposed to said reflective surface, and illuminating means disposed in said bore, said reflective surface adapted to reflect the rays of light therefrom through said covering means, and means for ventilating the canalization formed by said successive bores.
7. The combination with a structure to be illuminated, of a plurality of illuminating units built into said structure, and comprising container members, each provided with a bore communicating with the bore of the adjacent unit, said bore having a glazed reflective surface, means pervious to light covering the side of said containers opposed to said reflective surface, and illuminating 75 means disposed in said bore, said reflective surface adapted to reflect the rays of light therefrom through said covering means, and a channel in said bore adapted to receive condensed moisture formed in said bore.
8. A lighting unit of the character described, comprising an open end container member U-shaped in cross section and open at its upper side, and having a bore provided with a reflecting inner surface, means 80 pervious to light covering the upper open side of said container member opposed to said reflecting surface, supporting means and illuminating means supported thereby, said reflecting surface adapted to reflect the rays of light therefrom through said means pervious to light, said container being provided in its side walls with opposed pockets adapted to constitute auxiliary supporting means for said illuminating means.
9. The combination with a tank adapted to contain water, of a plurality of illuminating units built into said structure, and comprising container members each provided with a bore communicating with the 85

bore of the adjacent unit, said bore having an inner reflective surface, said units being provided with lateral supporting ledges, means pervious to light supported on said ledges, and covering the side of said container member opposed to said reflective surface, illuminating means disposed in said bore, said reflective surface adapted to reflect the rays of light therefrom through

said means pervious to light, and interlocking means on said ledges, and said means supported thereon forming a water-tight connection between said ledges and said means.

In testimony that I claim the foregoing 15 as my invention, I have signed my name.

GABRIEL E. ROHMER.
